UNITED STATES PATENT OFFICE.

PAUL M. HOTCHKIN, OF CHICAGO, ILLINOIS.

SUSPENDING DEVICE FOR LIGHTING FIXTURES.

Application filed August 29, 1921. Serial No. 496,213.

The present invention has to do with electrical lighting fixtures of the suspended type, and has particular reference to the suspending devices or canopy structures thereof.

The ordinary form of suspending device of the character referred to is difficult to wire. Much time and labor are involved in effecting this, and especially when fitting the canopy in position at the point of installation. This is due to the difficulty of threading the wires in the canopy. To overcome these objections the present invention contemplates an improved form of canopy so constructed and designed as to facilitate the general assembly of the parts and by which, after the fixture has been suspended from the canopy structure, the current leads of the fixture may be easily and quickly threaded into the canopy for connection with the circuit wires at the outlet box.

A further object of the invention is to provide a canopy construction wherein is included novel and efficient means for locking the fixture-suspending chain to the canopy structure, and thereby to preclude separation of the chain therefrom with consequent possible injury to the fixture.

Other objects and advantages will appear as the nature of the improvements is better understood, the invention consisting substantially in the novel construction, combination and arrangement of parts hereinafter fully described, illustrated in the accompanying drawings, and finally pointed out in the appended claims.

A practical form of the invention is disclosed herein, but this is not to be taken in a limiting or restrictive sense. It delineates to the art a concept of the appropriation of the invention to the purposes for which the latter is contemplated.

In the drawings Fig. 1 is a side elevation of a lighting fixture constructed in accordance with the present invention.

Fig. 2 is a transverse sectional view on an enlarged scale of the canopy construction disclosed in Fig. 1.

Fig. 3 is a detailed sectional view, as on the line 3—3, Fig. 2.

Fig. 4 is a sectional plan view as on the line 4—4, Fig. 2.

Fig. 5 is a transverse sectional view of the chain support, on the line of section of Fig.

2, portions being omitted to disclose more clearly the interior construction of the support.

Referring now in detail to the accompanying drawings, the numeral 10 designates the suspending chain commonly found in indirect lighting fixtures of the suspended type. This is connected at its lower end to the usual socket shell 11 in which the illuminating element 12 is positioned, and from which a plurality of downwardly extending supporting arms 13 are projected for sustaining the bowl 14 in associated relation with the socket shell 11. The chain 10 is connected to the canopy structure 15, and it is the latter with which the present invention is more directly concerned. Referring, therefore, to Figs. 2, 3 and 4, the features of this structure will be more readily apparent. The same includes the usual suspending device 16 commonly found in an outlet box 17 into which the circuit wires (not shown) are led. Associated with the suspending device 16 is a threaded bushing 18 to which is connected a coupling 19, and depending from the lower end of said coupling is a threaded bolt 20. To the lower end of the bolt 20 is detachably connected a chain support 21. This is commonly known in the art as the "hickey". The upper end of the chain support 21 is provided with a screw threaded bore 22 into which the lower end of the bolt 20 is fitted, and after the support 21 has been screwed on to the bolt 20 to the required extent a lock nut 23 is tightened upon the support 21 to prevent turning of the latter.

The lower end of the chain support 21 is cut out to provide a downwardly opening slot 24 which is of relatively large width in order to receive the upper link of the chain 10 and to permit this link freely to enter the same. At substantially the mid-portion of the support 21 the same is reduced in diameter to provide a shouldered boss 25 the exterior of which is screw threaded, and mounted on said boss 25 is a retaining ring 26 having an annular bead 27 which forms a support for the lower end of the canopy 28.

Loosely mounted in the support 21, and extending transversely of the slot 24 thereof at a point adjacent to the top of said slot, is a suspending pin 29. The length of this pin is slightly less than the diameter of the boss

25, so that the ends of the pin 29 lie within the boss and are adapted to be covered by the retaining ring 26 when this is applied to the boss. Thus the pin 29 is prevented being displaced from the boss, and connection of the chain 10 with the support 21 is maintained.

To permit threading of the current leads, designated by the numeral 30, through the support 21 and into the space within the canopy 28, the support 21 is provided with a pair of diagonally opposed conductor passages 31. These passages are arranged at opposite sides of the slot 24, the upper ends thereof opening at the sides of the support 21, while their lower ends, and a portion of each passage, extend into communication with the slot 24. Regardless, therefore, of the fact that the chain 10 is connected to the support 21 by the pin 29, it is possible for one of the current leads 30 to be threaded into the lower end of each of the passages 31 and to be pushed upwardly therethrough into the space normally enclosed by the canopy 28. This, of course, is effected before the canopy 28 has been pushed up into its position next to the ceiling or other point from which the fixture is suspended, and when the current leads 30 have been thus threaded 35 they may be easily connected to the circuit wires at the outlet box 17. After this has been done the canopy 28 is pushed up into position, and the retaining ring 26 screwed upon the boss 25, in which position the annular bead 27 thereof engages the lower end of the canopy 28 and holds the latter in position.

From the foregoing description it will be apparent that the herein described invention provides a canopy construction which is constructed and designed to facilitate the general assembly of the parts and by which, after the fixture has been suspended from the canopy structure, the current leads of the fixture may be easily and quickly threaded into the canopy for connection with the circuit wires at the outlet box. Furthermore, the invention provides a construction by which the fixture-suspending chain is sufficiently locked to the canopy structure so as to be precluded from becoming separated therefrom, and this prevents injury to the fixture due to separation of such chain from the canopy structure.

55 I claim:

1. In a canopy construction for lighting fixtures, the combination with a suspensory device, of a chain support connected thereto, said support being provided at its lower end with a downwardly opening slot for receiving the suspending chain of the fixture, said support also being provided with diagonally disposed passages therethrough for receiving the current leads of the fixture and to permit their threading through the support while

the suspending chain is engaged therewith, one of said passages being arranged at each side of said slot and having its lower end in communication therewith and its upper end opening at the exterior of said support. 70

2. In a canopy construction for lighting fixtures, the combination with a suspensory device, of a chain support connected thereto, said support being provided at its lower end with a downwardly opening slot for receiving the suspending chain of the fixture, said support also being provided with diagonally disposed passages therethrough for receiving the current leads of the fixture and to permit their threading through the support 75 while the suspending chain is engaged therewith, one of said passages being arranged at each side of said slot and having its lower end in communication therewith and its upper end opening at the exterior of said support, means for detachably engaging the chain with said support, and means for locking said engaging means in the support. 80

3. In a canopy construction for lighting fixtures, the combination with a suspensory 85 device, of a chain support connected thereto, a chain associated with said support, a pin loosely mounted in said support and from which the said chain is suspended, and means associated with said support for locking said pin against displacement. 90

4. In a canopy construction for lighting fixtures, the combination with a suspensory device, of a chain support connected thereto, a chain associated with said support, a pin 10 displaceably mounted therein and detachably connecting said chain to the support, and a retaining ring detachably connected to said support and co-operating therewith to prevent displacement of the pin from the support to lock the chain to the support. 10

5. In a lighting fixture of the class described, the combination with a suspensory device, of a chain support connected thereto, a fixture chain associated with said support, a pin displaceably mounted in the support and detachably connecting said chain to the support, a canopy surrounding the support and said suspensory device and a retaining ring detachably connected to said support and co-operating therewith to prevent displacement of the pin from the support to lock the chain to the support, said retaining ring having means adapted to engage the canopy to hold the same in applied 11 position. 12

6. In a lighting fixture of the class described, the combination with a suspensory device, of a chain support connected thereto, a fixture chain associated with said support, a pin displaceably mounted in the support and detachably connecting said chain to the support, a canopy surrounding the support and said suspensory device, and a retaining ring detachably connected to said support 13 14

and co-operating therewith to prevent displacement of the pin from the support to lock the chain to the support, said retaining ring having an annular bead adapted to engage the lower end of the canopy to hold the latter in applied position.

7. In a canopy construction for lighting fixtures, the combination with a suspensory device, of a fixture support connected thereto and provided with a downwardly-opening slot for receiving the suspending element of the fixture, a pin loosely mounted across said slot for detachably connecting the suspending element to said support, and means covering the ends of said pin and obstructing movement thereof for preventing displacement of the pin from the support, whereby to lock the suspending element to said support.

20 8. In a canopy construction for lighting

fixtures, the combination with a suspensory device, of a fixture support connected thereto and provided with a downwardly-opening slot for receiving the suspending element of the fixture, a pin loosely mounted across said slot for detachably connecting the suspending element to said support, said pin being of less length than the transverse dimension of the support, whereby the ends of the pin terminate short of the sides of the support when the pin is positioned in the latter, and a retaining ring associated with said support and covering the ends of the pin to obstruct outward movement thereof for preventing displacement of the pin from the support, whereby to lock the suspending element to said support.

In testimony whereof I have hereunto subscribed my name.

PAUL M. HOTCHKIN.
